LOCKING MEANS FOR DISTRIBUTORS

Edward Rick and Joseph Bonnie, Fresno, Calif.

Application September 19, 1934, Serial No. 744,742

15 Claims. (Cl. 200—19)

The present invention relates to distributors for internal combustion engines and has for its primary object to provide means for locking the distributor cap against unauthorized removal, to simultaneously lock the contact points of the distributor out of engagement to positively break the circuit leading to the distributor and to simultaneously short circuit the ignition system should the ignition circuit be bridged around the ignition switch in an effort to operate the motor while the switch is off or in locked position.

A further object is to provide a mechanism of this character which may be controlled and operated by the ignition switch on the instrument board of a vehicle or which may be operated by means of a key or similar device at the distributor casing.

A further object is to provide a device of this character which is efficient and practical in operation, relatively inexpensive to install in use and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which

Figure 1 is a side elevational view of a distributor embodying my invention with the cover cap shown in section,

Figure 2 is a sectional view taken substantially on a line 2—2 of Figure 1,

Figure 3 is a similar view with the locking cap removed,

Figure 4 is a group perspective view of the cover cap, locking cap and upper surface of the distributor base,

Figure 5 is a bottom plan view of the locking cap,

Figure 6 is a detail of the locking shaft, and

Figure 7 is a detail section showing the grounding wire and terminal carried by the distributor cap.

Referring now to the drawings in detail wherein for the purpose of illustration I have disclosed a preferred embodiment of our invention, the numeral 5 designates a distributor base of conventional construction having the shaft 6 extending upwardly therethrough and upon which is mounted the usual cover cap 7 held in place by the spring clips 8. The distributor base has its upper face provided with a plate 9 which carries the usual make and break contacts 10, one of said contacts being carried by a pivoted arm 11 nor-

mally urged into engagement by a spring 12 and moved out of contacting position by the cam surface 13 provided on the upper end of the shaft 6. The construction and operation of such circuit breakers is conventional and accordingly no detailed explanation thereof is deemed necessary.

The plate 9 is also provided with a pair of diametrically oppositely disposed openings 14 having angular extensions 15 at one end for receiving a pair of latches 17 depending from the under side of a locking cap 18.

The latches 17 have angular feet 19 formed on their lower ends for entering the extensions 15 of the openings 14. A third locking latch 20 is also carried by the cap 18 for entering an opening 21 also formed in the plate 9.

It will be apparent from an inspection of Figure 4 of the drawings that upon the placing of the cap 18 in position with the locking latches inserted in their respective openings, that a partial turn of the cap will move the feet of the lugs under the edge of the plate 9 and accordingly lock the cap in position. This turning of the cap is accomplished by means of an arm 22 also depending from the cap 18 and insertable through a slotted opening 23 of the plate 9 into a recess 24 of a shaft 25 which is journaled in an extension 26 projecting from one side of the casting 5. The shaft 25 may be operated in any suitable manner to cause a partial rotation thereof which, through its connection with the arm 22 will cause a partial rotation of the locking cap 18 to move the latches 17 and 20 into and out of locking position with respect to the distributor plate 9. In the present embodiment of the invention this rotation of the shaft 25 is accomplished by means of a flexible shaft 27 which extends to the ignition switch for the engine and may be attached to said switch in such a manner that the operation of the switch will produce the desired rotation of the shaft 25.

The locking cap 18 is provided with a central opening 28 through which the shaft 6 extends in order that the usual rotor 29 for the distributor may be mounted thereon above the cap 18, as more clearly illustrated in Figure 1.

Depending from the under side of the cap are a pair of contact locking members 30 which are positioned adjacent the pivoted arms 11 of the circuit breaker and normally out of operating engagement therewith. These locking members will engage the arms 11 to move the contacts 10 and retain the same out of contacting position upon the locking movement of the cap 18 in a clockwise direction, as will be clearly apparent

from an inspection of Figure 3 of the drawings.

An arm 31 is pivoted to the plate 9 and extends upwardly through a guide 32 secured to the inner side of the cap 18 with its upper end projecting above the cap through an opening 33. The greater portion of the arm 31 is provided with an insulated sleeve 34 leaving the upper extremity of the arm exposed as shown at 35. This exposed end of the arm is adapted to contact a pin 36 projecting from the inner wall of the cover cap 7 when the cap 18 has been moved into its locked position. The pin 36 is connected to the central terminal of the distributor by means of an embedded wire 38 whereby it will be apparent that the current entering the distributor will be grounded through the casing 5 when the device is in locked position. The locking cap 18 is provided with a pair of locking pins 39 projecting outwardly from the opposite sides thereof for entering in bayonet slots 40 formed in the inner walls of the cover cap 7.

Accordingly the locking movement of the locking cap 18 will likewise lock the cover cap 7 against removal.

25 A pin 41 also projects from the inner wall of the cover cap 7 for engaging the upper surface of the locking cap 18 to prevent upward movement thereof during its rotation or turning movement.

30 It is to be understood that in place of the flexible cable 27 for operating the shaft 25 a key control lock may be mounted in the extension 26 for accomplishing the desired locking and unlocking movement of said shaft.

35 We claim:

1. A distributor lock comprising a base, a cover cap thereon, a locking cap enclosed by said cover cap and mounted for bodily movement independent of the base and cover cap, and latch means 40 between the locking cap and the base, said latch means being operable by the bodily movement of said locking cap.

2. A distributor lock comprising a base, a cover cap thereon, a locking cap mounted for bodily movement upon the base, latch means between the base and the locking cap and operable by the bodily movement of the latter, and means operable outwardly of the base for causing the bodily movement of the locking cap.

50 3. A distributor lock comprising a base, a cover cap thereon, a locking cap mounted for bodily movement upon the base, latch means between the base and the locking cap and operable by the bodily movement of the latter, a locking mechanism between the cover cap and the locking cap and also operable by the bodily movement of the latter, and means operable outwardly of the base for causing the bodily movement of the locking cap.

60 4. A distributor lock comprising a base, a cover cap thereon, a locking cap enclosed by said cover cap and mounted for bodily movement on said base, pin and slot locking connections between the cover cap and locking cap and between the locking cap and the base, and operable upon the bodily movement of the locking cap, and means operable outwardly of the base for causing the bodily movement of the locking cap.

70 5. A distributor lock comprising a base, a cover cap thereon, a locking cap enclosed by said cover cap and mounted for bodily movement on said base, locking means for the cover cap and the locking cap and operable by the bodily movement of the latter and means carried by the locking cap for securing the contact points of

the distributor out of engagement when said locking cap is in locked position.

6. A distributor lock comprising a base, a cover cap thereon, a locking cap enclosed by the cover cap and mounted for bodily movement on the base, and a plurality of locking mechanisms operable by said bodily movement of the locking cap for locking both of said caps and for securing the contact points of the distributor out of contacting position.

10 7. A distributor lock comprising a base, a cover cap thereon, a locking cap enclosed by the cover cap and mounted for bodily movement on the base, locking mechanisms operable by the bodily movement of the locking cap for locking both of said caps and arms carried by the locking cap for moving the contact points of the distributor out of engagement during said cap locking movement.

15 8. A distributor lock comprising a base, a cover cap thereon, a locking cap enclosed by the cover cap and mounted for bodily movement on the base, locking mechanisms operable by the bodily movement of the locking cap for locking both of said caps and arms carried by the locking cap for moving the contact points of the distributor out of engagement during said cap locking movement and means operable outwardly of the base for causing the bodily movement of the locking cap.

20 9. A distributor lock comprising a base, a cover cap thereon, a locking cap enclosed by the cover cap and mounted for bodily movement on the base, means for locking said caps, means for grounding the electric circuit of the distributor, 25 both of said means being responsive upon the movement of said locking cap and means operable outwardly of the base for causing the bodily movement of the locking cap.

30 10. A distributor lock comprising a base, a cover cap thereon, a locking cap enclosed by the cover cap and mounted for bodily movement on the base, means for locking said caps, means for locking the contact points of the distributor out of engagement, means for grounding the electric circuit of the distributor, all of said means being responsive upon the movement of said locking cap, and means operable outwardly of the distributor for causing the bodily movement of the locking cap.

40 11. A distributor lock comprising a base, a cover cap thereon, a locking cap enclosed by the cover cap and mounted for bodily movement on the base, means for locking said caps, means for locking the contact points of the distributor out of engagement, means for grounding the electric circuit of the distributor, all of said means being responsive upon the movement of said locking cap, and means operable outwardly of the distributor for causing the bodily movement of the locking cap, said circuit grounding means comprising a projection carried by the cover cap having a circuit connection with the lead in terminal of the distributor, an arm pivoted to the base, and guide means on the locking cap for swinging said arm into and out of engagement with the pin upon the locking and unlocking movement of the cap.

50 12. A distributor lock comprising a base having a plurality of angular slotted openings therein, a cover cap thereon, a locking cap enclosed by the cover cap and mounted for bodily movement on the base, a plurality of angular latches carried by the locking cap and inserted in said openings, a pin and slot connection between said 55 60 65 70 75 80 85 90 95 100 105 110 115 120 125 130 135 140 145 150 155 caps, and means operable outwardly of the distributor for causing the bodily movement of the locking cap whereby to lock the caps to each other and to lock the locking cap to the base.

5 13. A distributor lock comprising a base having a plurality of angular slotted openings therein, a cover cap thereon, a locking cap enclosed by the cover cap and mounted for bodily movement on the base, a plurality of angular latches carried 10 by the locking cap and inserted in said openings, a pin and slot connection between said caps, and means for producing a bodily movement of the locking cap and comprising a shaft projecting from the base and an operating connection between the shaft and the locking cap.

15 14. A distributor lock comprising a base, a cover cap thereon, a locking cap enclosed by the cover cap and mounted for bodily movement on the base, recesses in the base and cover cap, locking 20 members rigidly carried by the locking cap and engageable with the recesses for locking the caps

to each other and for locking one of the caps to the base upon such bodily movement of the locking cap and means operable outwardly of the distributor for causing such bodily movement.

15. In a distributor, a metal base, a cover cap 5 of insulating material carrying an electric terminal for a lead-in cable, a rotating contact arm having constant electrical connection with said terminal, a member within the distributor rotatable from a point outside thereof, and a switch 10 device within the distributor independent of said rotating contact and including a second terminal electrically connected with the first terminal, and a cooperating switch arm having electrical connection with the base and movable by rotation of the member into contact with the second terminal to thereby ground the circuit entering the distributor through the first terminal. 15
